(57) **CLAIM**

The ornamental design for a pop-up knob, as shown and described.

DESCRIPTION

FIG. 1 is a front perspective view of a pop up knob showing my new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The bottom view of the pop-up knob shown in the drawing figures does not form part of the claimed design. Drawing features shown in dashed lines do not form any part of the design claimed herein.
